ACTUATOR

Sven Svenson, deceased, late of San Francisco, Calif., by Selma Svenson, administratrix, San Francisco, Calif., assignor to George Svenson and Carl Svenson

Application December 17, 1933, Serial No. 246,378

2 Claims. (Cl. 175—341)

The invention relates to actuators of the general type shown in Patent No. 2,093,689, issued to Sven Svenson on September 21, 1937, entitled "Motor actuator," and is particularly concerned with a means for electrically operating a device of the character of a stapling machine, for example, automatically upon the insertion into the machine of a sheet or sheets to be stapled or stamped or comparably operated upon.

Where only a few sheets of easily perforable paper are to be stapled together, the amount of power required is relatively small and the difficulties of supplying electrical actuation are not great. But when the number of sheets to be stapled together is large and the paper is not readily perforable, then the amount of power instantaneously required becomes very great indeed, so that there is difficulty in supplying a source of power which is acceptable for desk or office use and which does not require so much current as to give trouble with electrical contacts and other parts of the circuit, yet which is of a reasonable character from the standpoints of cost of manufacture, maintenance and operation. But even a machine which is readily usable under heavy duty conditions and is particularly designed therefor may not give entirely satisfactory service if it is indiscriminately utilized for very light operations, such as stapling only one or two sheets.

It is therefore an object of the invention to provide an actuator which with equal facility is usable with very light loads or very heavy loads.

Another object of the invention is to provide an actuator which is of reasonable size and character yet is capable of exceedingly heavy duty operation.

An additional object of the invention is to provide an actuator which is initially energized by the insertion of a sheet to be treated and which has adequate power so controlled as to perform heavy duty or light duty operations.

Another object of the invention is to provide an actuator which is useful in connection with various appliances other than staplers, such as stamps, perforators and the like.

The foregoing and other objects are attained in the embodiment of the invention illustrated in the drawings, in which—

Fig. 1 is a side elevation of an actuator in accordance with the invention;

Fig. 2 is a front elevation of the device shown in Fig. 1;

Fig. 3 is a side elevation of the actuator with the enclosing casing removed;

Fig. 4 is a plan of the structure shown in Fig. 3; Fig. 5 is a cross-section on a longitudinal, vertical, central plane, indicated by the line 5—5 of Fig. 4, showing the actuator in de-energized position;

Fig. 6 is a view similar to Fig. 5 yet showing the actuator in energized position.

In its preferred form, the actuator of this invention is usable in connection with a stapling machine which is mounted on a base in connection with the actuator, the actuator itself preferably including an electromagnetic coil having a pair of armatures which are simultaneously energized to move into the coil and which are both coupled to a linkage for actuating the stapler.

While the actuator of this invention is by no means restricted to use with stapling machines, or restricted to use only with a special type of stapling machine, it is convenient to describe it in connection therewith and hence it is so illustrated herein. In the present embodiment there is included a base 6 having a plurality of supporting feet 7 and on which a removable enclosing housing 8 is detachably mounted. The housing is provided along its forward portion with a receiving slot 9 into which material such as a plurality of sheets to be stapled can be inserted. The sheets are pushed into the slot 9 manually until they abut a finger 11 in their path of advance, which energizes the device to effectuate a stapling operation, following which the sheets are withdrawn. The cycle can be repeated with subsequent insertion of sheets.

Within the casing 8 there is situated a stapling machine 12 which is a complete commercial article having its own base 13 provided with feet which fit into suitable sockets in the base 6. The stapler is completely actuated by depression of a lever 17 which pivots about a hinge 18 on the base 13 and which, when the stapler is not utilized in this environment, is ordinarily actuated by manual depression of a pad 19.

In accordance with the invention, there is secured to the base 6 a pair of uprights 21 and 22, spaced apart so that they receive the stapler 12 between them, yet extending upwardly to provide bearing supports 23 for a cross-shaft 24. Projecting from the cross-shaft are radial arms 26 and 27 which between them support a rotating roller 28 abutting the upper surface of the lever 17. The shaft 24 has a squared end 29 to which a hand crank (not shown) can be attached through an aperture 31 in the side of the housing 8, so that upon operation of the hand crank

the shaft 24 is rotated and by depression of the roller 28 the stapler is manually actuated.

This manual actuation is not ordinarily utilized, and in order to provide power actuation, the shaft 24 carries a pair of arms 32 and 33 between them carrying a swivel block 34 which is rotatable on a cross-pin 36 mountable alternatively in either of two pairs of apertures 37 and 38 in the arms 32 and 33. The block 34 has an interiorly threaded extension 39 into which is screwed a pitman rod 41 having a flattened terminus 42 extending into the forked end 43 of an armature bar 44 to which the pitman is articulated by a pivot pin 46. The armature bar is preferably square in transverse cross-section and at its opposite end is connected by a pin 47 to an armature 48 preferably fabricated of a plurality of metal sheets held in a pack by rivets 49. The armature 48 is preferably itself rectangular in transverse cross-section and is slidable within a rectangular tube 51 of non-magnetic material. Likewise slidable within the tube 51 is a second armature 52 fabricated of a bundle of metal plates secured by rivets 53 and having an interior recess 54 to accommodate the pitman 41 and the bar 44. Fastened to the armature 52 is a pair of pitmans 56 and 57 each of which is secured by a pin 58 and both of which extend to pivotal connections by pins 59 and 61 to extensions of the arms 26 and 27 wherein a pair of apertures 62 and 63 are provided for alternative utilization.

In accordance with the invention, there is provided means for electromagnetically energizing the two armatures 48 and 52 simultaneously. The arrangement of such means is so that the center of the electromagnetic field substantially coincides with the center of the tube 51. For that reason, around the tube 51 is provided an electromagnetic coil 66 with which cooperates a field frame 67 preferably made of laminated metal sheets secured together by screw fastenings 68 and provided with feet 69 for mounting the assembly on the base 6. When the coil 66 is energized, the two armatures 48 and 52 are moved toward each other and toward the center of the tube 51 so that the pitmans 56 and 57 and the pitman rod 41 are simultaneously actuated in opposite directions to rotate the shaft 24 and thus to actuate the stapler. While the speed of operation of the armatures 48 and 52 can be somewhat regulated by the air cushion or dashpot effect due to the movement of the armatures into the interior of the tube, there is preferably provided no material restriction by this means and consequently there is afforded a passage 71 in the bar 44 to establish communication between the chamber 72 within the tube and between the armatures and the exterior, so that air may flow freely inwardly and outwardly from such chamber, although the passage can be restricted if desired and such restriction can be operable equally in both directions of airflow or can have more effect in one direction of airflow so that one directional movement of the armatures is restricted more than the other.

With this arrangement, when the coil 66 is energized the armatures 48 and 52 are pulled with a great force into a location where the flux is of maximum density, so that with a small expenditure of electric current the stapler is effectively actuated. Furthermore, the relationship of the lever arms 26 and 32 is such that the force exerted by the electromagnet is correctly related to that required by the stapler, so that

the mechanism is given a thorough and satisfactory actuation.

In order that the coil 66 will be suitably energized upon insertion into the stapling machine 5 of a sheet to be operated upon, there is provided an electric circuit and associated instrumentalities which will produce the requisite result. Current from a suitable source is conducted to the machine through a lead which is connected to the coil 66. From the coil a lead extends to a brush 78 which is mounted on a block 79 secured between a pair of brackets 81 and 82 mounted on the field frame 67. In rotatable contact with the brush 78 is a switch barrel 80 preferably fabricated of insulating material and mounted on a pin 83 journaled in the brackets 81 and 82. Forming an element of the barrel 80 is a metallic conducting plug 84 with which the brush 78 is adapted to contact. Axially displaced from the brush 78 is a brush 86 likewise mounted on the block 79 and forming a continuation of the circuit.

To ensure that the interruption of the circuit to the coil 66 is made at the appropriate time despite the fact that perhaps the material being treated is not promptly withdrawn, and despite variations in the thickness of the materials which might vary the stroke of the stapling mechanism, there is provided a means which is responsive to the actuation of the machine for interrupting the circuit. To this end, on the rod 41 is mounted a collar 146 which is adjustably positionable by manipulating a set-screw 147, and there is likewise mounted on the rod a loose sleeve 148 which is separated from the collar by an interposed cushion washer 149. Normally the sleeve and the collar are urged together by a coil spring 151 one end of which engages a pin 152 in the collar 146 and the other end of which engages a pin 40 153 in the sleeve 148.

The sleeve 148 is in the nature of an inertia weight, so that when the rod 41 is rapidly accelerated toward the left in Fig. 3 the weight 148 is accelerated therewith; yet when the rod 41 stops 45 suddenly during the stapling operation, the weight 148 continues to slide along the rod 41. This tensions the spring 151, and the weight 148 is subsequently returned by the spring tension. In the interim, however, the weight 148 comes into 50 abutment with a loop 154 which encompasses the rod 41 and is formed at the end of a rod 156 connected by a pivot pin 157 to an arm 158 extending from the drum 80. A felt washer 159 is interposed as a cushion between the loop 154 and the 55 swivel block 39.

The relationship of the parts is such that when the coil is energized and the rod 41 is actuated, the felt washer 159 is translated with the rod 41, yet the loop 154 retains its position. But as soon 60 as the rod 41 stops, having completed the stapling operation, the weight 148 continues on and strikes the loop 154 translating it and the rod 156 toward the left in Fig. 3, thus rotating the contact drum 80. This rotation causes the conductor 84 to ride from under the conductor arms 78 and 86, thereby breaking the circuit and de-energizing the coil 66. The rotation of the drum 80 is sufficient to bring a groove 161 therein into position beneath the arcuate ends of the arms 78 and 86 so that the drum is held in contact-open position until such time as the standard return spring mechanism in the stapling device moves the arm 17 upwardly, rotates the shaft 24 in a clockwise direction as seen in Fig. 3, restores the 75 parts to their original position, and the felt

collar 159 again abuts the loop 154 and drives the rod 156 toward the right in Fig. 3 so that the drum 80 is rotated back into a position in which the conductor 84 is again in abutment with the contact arms 78 and 89. Thus the circuit is always broken by the inertia member 148 and without regard to the thickness of the material being stapled or otherwise treated, so that the interruption of the electric circuit takes place without regard to the character of the material being treated or the character of the stapling operation.

What is claimed is:

1. An actuator comprising a frame, a shaft journalled on said frame and having a pair of opposed cranks thereon, a sleeve mounted on said frame wholly at one side of the shaft with its axis at right angles to and in the same plane with the axis of said shaft, means for producing an electromagnetic field around the center of said sleeve, a pair of armatures mounted to slide within said sleeve, the armature nearer said shaft having an aperture therethrough, a single link pivotally connecting said nearer armature to one of said cranks, and another single link working freely through said aperture and pivotally connecting the farther one of said armatures to the other of said cranks, the angular relationship of said links and said cranks being such that the

operating leverage of said armatures is greater near operated position than at their unoperated position.

2. An actuator comprising a frame, a sleeve mounted on said frame, means for producing an electromagnetic field around the center of said sleeve, a shaft journalled on said frame beyond one end of said sleeve, the axis of said shaft being disposed substantially at right angles to and intersecting the sleeve axis, opposed cranks carried by said shaft, an armature reciprocable within said sleeve between the center thereof and the sleeve end near said shaft, a single link pivotally connecting said armature to one of said cranks, a second armature reciprocable within said sleeve between the center thereof and the sleeve end remote from said shaft, a second link pivotally connecting said second armature to the other of said cranks, the said first mentioned armature being apertured to permit the said second link to reciprocate freely through the first mentioned armature, and the angular relationship of the crank arms and connecting links being such that the operating leverage of said armatures is greater near operated position than at their unoperated position.
